UNITED STATES PATENT OFFICE

2,570,021

PARTS CLEANING MACHINE

Harold W. Beach, Abilene, Kans.

Application March 6, 1945, Serial No. 581,200

1 Claim. (Cl. 134—199)

1 This invention relates to a machine for cleaning production parts, or parts of machines and tools, and one of its objects is to provide a machine which will rinse the parts to be treated by sprays projected from different directions, to produce the maximum cleansing effect.

Another object of the invention is the provision of a parts cleaning machine with means for circulating the cleansing solution through the machine sprays, under air pressure supplied to a general reservoir or supply tank.

A further object of the invention is the provision of a parts cleaning machine, with means for filtering the cleaning fluid or solution and for returning filtered solution to the supply tank for reuse in the machine.

A still further object of the invention is the provision of a cleaning machine with a cover having drip collector beads formed on the internal face thereof, so that condensation can be drained back into main chamber.

With the above and other objects in view the invention consists in certain new and useful constructions, combinations, and arrangements of parts, clearly described in the following specification, and fully illustrated in the accompanying drawings, in which—

Figure 1 is a vertical sectional view through the machine, taken on a line 1—1 of Figure 4, looking in the direction of arrows.

Figure 2 is a vertical sectional view through the main supply tank, the associated valves, the main chamber drain and the solution filter.

Figure 3 is a detail plan view of a distributor.

Figure 4 is a horizontal sectional view taken on line 4—4 of Figure 1, looking in the direction of the arrows.

Figure 5 is a detail vertical sectional view of an adjustable spray nozzle.

Referring to the accompanying drawings, in which a practical example of my invention is shown, 5 designates supporting steel legs, which carry the dome-shaped bottom 6 of the cylinder wall 7, which is united to the marginal edge of the bottom by means of the joint seam 8.

At the center of the dome-shaped bottom wall 6 a drain opening 9 is formed and below this drain opening a drain vessel or container 10 is attached to the outer surface of the bottom 6. Over the dome-shaped bottom 6 a screen mesh fabric 11 is disposed, and the center of this screen mesh is pierced by means of the nozzle 12, which is adjustable in the tube 13, which is closed at its lower end. This tube 13 is equipped with a gland nut 14, to prevent leakage through the

joint established between the nozzle and the tube 13.

Around the nozzle 12 a spray ring 15 is arranged, and this ring is made up of companion sections 15a and 15b, which are coupled to each other by the connections 15c. The section 15a is supplied with cleansing fluid through the pipe 16, which is extended through the dome-shaped bottom wall 6, and sealed thereon by the clamp nuts 17. This pipe or conduit is then coupled with the distributor 18. From this distributor another pipe or conduit 19 extends through the dome-shaped bottom 6, and is coupled to the bottom of the tube 13, to supply cleansing fluid to the central spray nozzle 12.

Above the screen 11 a larger spray ring 20 is located, which includes the sections 20a and 20b, which are connected to each other by means of the couplings 20c. The section 20a is supplied with cleaning fluid from the pipe 21, which is extended through the side of the cylinder 1, and at its lower end is connected to the distributor 18. The section 20b is connected to the supply pipe 22, which is extended through the wall of the cylinder 1, and at its lower end is connected to the distributor 18. The section 15b of the lower spray ring 15 is connected to the supply pipe 24, which is extended through the bottom 6, and is then coupled to the distributor 18.

The filter 23 is coupled to the drain vessel 10 by the pipe 23a, and discharges into the pipe 26, which communicates with the valve housing 27, and this valve housing discharges into the supply tank 28.

The distributor 18 is coupled to the supply tank 28 by means of the pipe 29, which is equipped with a valve housing 30. The discharge pipe from the filter pierces the upper wall of the supply tank, above the level of the supply, and the feed pipe 29 which supplies the distributor 18, extends into the tank 28 well below its level of its supply.

Flow is maintained from the supply tank, which is shown to be located below the bottom 6, by means of air which is supplied under pressure through the spring pressed valve 30, which operates in the valve housing 31, to which the air conduit or pipe 32 is connected.

Flow through the air supply conduit 32 is manually controlled by means of the spring pressed valve 33, which works in the housing 34, to which the intake pipe 35 is connected. The stem of the valve 33 is extended through the gland nut 36 and is engaged by the link 37, which has its lower end pivotally connected to the lever 38, which is pivoted at 39 to one of the supporting legs 5.

3

When pressure air is supplied to the valve housing 34 and the foot operated valve 33 is operated, by the depression of the lever 38, pressure air will flow into the supply tank, thus producing pressure over the contained cleaning fluid, and this pressure will tend to force the cleaning fluid through the distributor and thence through the central nozzle and the spray rings.

The force of the sprays may be thus increased or diminished at will, by varying the release of the air pressure, and by increasing the pressure of the air used, or by using lower air pressure.

All fluid supplied to the upper spray ring will flow into the drain vessel, and thence to the filter. But some of the fluid supplied to the lower spray ring will flow through the filter.

The cylinder wall 7 is closed by means of the cover 40, which is equipped with a spring closed blow-off valve 41. This cover is provided with an interior lining or facing 42, of sheet metal, which is formed to provide annular drain collecting beads or rings 43, which are located near the outer edge thereof, while the central area of this facing plate is dished upwardly to provide a self draining dome 44.

The cover is hinged on one side at 45, and is clamped at 46 on the opposite side, and the upper end of the cylinder wall 7 is formed with an internal drainage flange 47 which lies contiguous to the drain collecting rings or beads 43.

The small parts to be cleaned are placed on the screen, cleansing fluid is supplied to the tank 28, through the filler 28a, and air pressure is supplied to the tank, through the operation of the manual or foot operated valve. Immediately after the cleansing fluid is released by the force of the pressure air, sprays flow from the central nozzle, the lower spray ring and the upper spray ring. In this way the upper and bottom surfaces of the parts supported on the screen are exposed at the same time to the scouring and rinsing action of the cleaning fluid, under such controlled pressure as will best suit the work.

All used cleaning fluid is returned to the filter and then to the supply tank, after being filtered, and may be used repeatedly, until its usefulness ceases.

My improved machine reduces the time and cost of cleaning parts, and improves the work as

4

a result of the use of a controlled pressure for applying the cleaning fluid through sprays against the work. The air can be accumulated in suitable air tanks, by automatic air compressing equipment, governed to maintain a controlled pressure limit.

Having described my invention I claim as new:

A cleaning machine comprising a vessel, a horizontally disposed article supporting grid supported within the vessel intermediate the upper and lower ends thereof, a lower horizontally disposed spray ring supported within the vessel immediately below the supporting grid, said spray ring having upwardly directed spray passages therein, an upper horizontally disposed spray ring supported within the vessel in spaced relation to the supporting grid, said upper spray ring being concentric about the lower spray ring and having downwardly directed spray passages therein, a spray nozzle extending upwardly and axially through the lower spray ring and supporting grid, said spray nozzle having upwardly directed spray passages therein and a common source of liquid supply coupled to the spray rings and nozzle for supplying spray liquid thereto.
